UNITED STATES PATENT OFFICE.

JOHN F. OHMER, OF DAYTON, OHIO.

MECHANISM FOR OPERATING FARE-REGISTERS.

SPECIFICATION forming part of Letters Patent No. 640,800, dated January 9, 1900.

Application filed August 1, 1899. Serial No. 725,800. (No model.)

To all whom it may concern:

Be it known that I, JOHN F. OHMER, a citizen of the United States, residing at Dayton, in the county of Montgomery and State of Ohio, 5 have invented a new and Improved Mechanism for Operating Fare-Registers, of which the following is a specification.

The object of my invention is to avoid the multiplicity of cords heretofore necessary to 10 the operation of a fare-register arranged to register separately fares of several kinds. In the use of a number of cords great caution is necessary on the part of the conductor in order that he may not register a wrong fare. 15 In place of such cords I make use of a common operating rod or shaft which may be supported in any suitable manner, preferably from the roof of the car, and is arranged to be operated by a single handle in such a 20 way that the movement of the handle to any certain predetermined point will so move the rod or shaft longitudinally that a second motion of the handle in a direction at right angles to its first motion will effect the registry 25 of any desired one of a number of different fares.

The accompanying drawings, illustrating my invention, are as follows:

Figure 1 shows the lower portion only of a 30 fare-register and means for communicating motion to the several sets of registering mechanisms thereof from the different individual operating devices contained within the case B. In Fig. 1 the front of the case 35 B is removed. Fig. 2 shows in top view the parts seen in Fig. 1 and the operating-rod S and its attachments with the top piece b' of the case B removed. Fig. 3 shows in an enlarged face view the operating-handle h² and 40 the indicator-plate d' and the rod S located between the supporting-brackets h'. Fig. 4 shows in perspective the grooved top piece b' of the case B.

Similar letters refer to similar parts throughout the several figures.

Referring to the drawings, R represents the lower portion of a register of any desired construction, preferably such as shown in United States Patent No. 582,366, dated May 11, 1897, 50 and issued to J. F. Ohmer and H. Tyler.

a b c d e represent the fare pulls or devices, by the operation of which each particular fare is registered separately.

The essential feature of my present invention consists in means whereby the longitudinal and rotary movement of the operating-rod is caused to select and operate the desired one of these fare-pulls a b c d e. While these fare-pulls may be operated directly from mechanism on the rod, still I have found it 55 desirable to locate the register near the center of one end of the car, so as to be out of line with the operating-rod. In such a case I make use of a series of slides or equivalent devices which are operated directly from the 60 rod and also mechanism for communicating motion from each of such slides to each of the fare-pulls in the register. In the present case I have shown such an arrangement. From these fare-pulls a b c d e extend a series 65 of cords f g h i j, respectively, working around under suitable grooved guide-pulleys and connected to the left-hand ends of the slides k l m n o, respectively. These slides k l m n o work freely in the grooves formed in the under surface of the cap-piece b' of the case B. 70 These slides k l m n o are supported by the horizontal extension formed at the top of the left-hand side of the case B. In this case B are secured the bearings for the operating-rod S. This operating-rod S has secured thereon within the case B the finger b² 75 and the sector of a disk b³. Just beneath this rod S there is seen a horizontal partition b⁴, secured within this case B. In this partition b⁴ are formed slots, through which the sector b³, secured on the shaft S, may be caused to pass by the rotation of the rod S over to the right. This finger b² is arranged to engage 80 these slides k l m n o only one at a time, when 85 by the longitudinal movement of the rod S the sector b³, secured thereon, is brought into a position where it will pass into the slots formed in this partition b⁴. This partition b⁴ coöperates with the sector b³ to prevent a ro- 90

95 tation of the rod S over to the right, except when such rod S is in a position to engage, by means of the finger b² thereon, some one of the slides k l m n o. This case B may be supported from the end of the car at such a height as to 100

cause this rod S to occupy a horizontal position when supported in bearings, as h' , which may be secured to the under side of the roof of the car. Of these brackets h' there may be any 5 desired number. I prefer to locate two of such brackets near the point of operation of the rod S by means of the handle h^2 , with one of such brackets h' on each side of the indicator-plate d' . This indicator-plate d' has extensions d^2 through which this rod S passes. The rod S is splined, so as to receive a feather 10 k' , secured in one or each of these bearings d^2 . This indicator-plate d' is prevented from longitudinal movement by means of the brackets 15 h' at each side thereof, while the shaft S, being splined, is capable of only longitudinal movement through the bearings d^2 , formed on the indicator-plate d' , as the feather k' , working in the spline in the rod S', prevents a rotation of the rod S relative to the indicator-plate d' . This rod S is capable of both longitudinal and rotary movement in the bearings formed on the lower ends of these brackets h' . An operating-handle h^2 is secured upon 20 this rod S and carries a spring-pointer s , in the upper end of which is journaled the roller r , arranged to enter the notches r' formed near the lower edge of the indicator-plate d' , whereby the shaft S' may be lightly held in 25 any desired position of longitudinal adjustment. Opposite each one of the notches r' is seen an indication as to the character of the fare that will be registered by the swinging of this shaft S by means of the handle h^2 when 30 the roller r has engaged the corresponding notch r' in this indicator-plate d' . It will of course be understood that of these indicator-plates d' , with the notches r' therein and the suitable fare indications thereon, there may 35 be any desired number, located at convenient points in the car, and all supported and operating in the manner already indicated and described.

In using my operating mechanism the conductor after receiving the fares moves the rod 45 S longitudinally by means of the handle h^2 thereon until the pointer s at the upper end of this handle is opposite the fare indication corresponding to the fare he has received, at which 50 time the roller r will have engaged the corresponding notch r' in this indicator-plate d' , serving to hold the rod S in the desired position of longitudinal adjustment. Then the conductor will swing the handle h^2 toward the 55 center of the car, thereby imparting a rotary motion over to the right to the rod S, and by this motion the finger b^2 will be caused to operate the desired one of the slides $k l m n o$, by means of which, through the cords $f g h i j$, 60 respectively, the desired individual fare-registering mechanism $a b c d e$ of the fare-register R will be operated.

What I claim is—

1. A series of independently - operating 65 parts each arranged to actuate a specific fare-

registering mechanism, a rod, means for supporting such rod and for imparting thereto both a rotary and a longitudinal movement, means on such rod for engaging and operating each one individually of such independently-operating parts when brought into operative relation thereto by the longitudinal movement of such rod, and means for preventing a rotative movement of such rod except when in position to actuate one of such independently-operating parts. 70

2. A series of independently - operating parts each arranged to actuate a specific fare-registering mechanism, a rod, means for supporting such rod and for imparting thereto both a rotary and a longitudinal movement, means on such rod for engaging and operating each one individually of such independently-operating parts when brought into operative relation thereto by the longitudinal movement of such rod, and means for indicating when the proper longitudinal movement has been imparted to such rod for actuating any desired one of such independently-operating parts. 80

3. A series of independently - operating parts each arranged to actuate a specific fare-registering mechanism, a rod, means for supporting such rod and for imparting thereto both a rotary and a longitudinal movement, 85 means on such rod for engaging and operating each one individually of such independently-operating parts when brought into operative relation thereto by the longitudinal movement of such rod, and means for preventing 90 a rotative movement of such rod except when in position to actuate one of such independently-operating parts, and means for indicating when the proper longitudinal movement has been imparted to such rod for actuating 95 any desired one of such independently-operating parts. 100

4. A series of independently - operating parts each arranged to actuate a specific fare-registering mechanism, a rod, means for supporting such rod and for imparting thereto both a rotary and a longitudinal movement, 110 means on such rod for engaging and operating each one individually of such independently-operating parts when brought into operative relation thereto by the longitudinal movement of such rod, and means contained 115 within the same case with such independently-operating parts, for preventing a rotative movement of such rod except when in position to actuate one of such independently-operating parts. 120

5. A series of independently - operating parts each arranged to actuate a specific fare-registering mechanism, a rod, means for supporting such rod and for imparting thereto both a rotary and a longitudinal movement, 125 means on such rod for engaging and operating each one individually of such independently-operating parts when brought into op- 130

erative relation thereto by the longitudinal movement of such rod, means contained within the same case with such independently-operating parts, for preventing a rotative movement of such rod except when in position to actuate one of such independently-operating parts, and means for indicating when the

proper longitudinal movement has been imparted to such rod for actuating any desired one of such independently-operating parts.
